GAME RACKET YOKE

William E. Portz, North Madison, and Pete Cosmos, Sr.,
Ashtabula, Ohio, assignors to True Temper Corpora-
tion, Cleveland, Ohio

Filed Nov. 4, 1974, Ser. No. 520,240

Term of patent 14 years

Int. Cl. D21—02

U.S. Cl. D34—5 ST

FIG. 1.

FIG. 4.

FIG. 5.

FIG. 6.

FIG. 2.

FIG. 3.

FIG. 1 is a front elevation of a game racket yoke showing our new design;

FIG. 2 is an enlarged three-quarter perspective view of the yoke showing the front, top, and one end thereof;

FIG. 3 is an enlarged three-quarter perspective view of the yoke showing the front, bottom, and one end thereof drawn to the scale of FIG. 2;

FIG. 4 is an enlarged top plan view of the yoke;

FIG. 5 is an enlarged front elevation of the yoke drawn to the scale of FIG. 4; and

FIG. 6 is an enlarged bottom plan view of the yoke drawn to the scale of FIG. 4.

The broken line representation of a game racket frame and strings in FIG. 1 is for purposes of illustrating environmental structure only.

We claim:

The ornamental design for a game racket yoke or similar article, as shown and described.
